Primary Examiner — Patricia A Palasik(74) *Attorney, Agent, or Firm* — Cozen O'Connor(57) **CLAIM**

The ornamental design for transmission cooler for automotive applications, as shown and described.

DESCRIPTION

FIG. 1 is a front view of a transmission cooler showing a new design in accordance with one embodiment;

FIG. 2 is a back view thereof;

FIG. 3 is a left view thereof;

FIG. 4 is a right view thereof;

FIG. 5 is a top view thereof;

FIG. 6 is bottom view thereof; and,

FIG. 7 is a front perspective view thereof.

The broken lines in the drawing figures show portions of the transmission cooler which form no part of the claimed design.

The shade lines in the figures show contour and not surface ornamentation.

1 Claim, 4 Drawing Sheets(56)
